UNITED STATES PATENT OFFICE

125,780

DESIGN FOR AN ASH HOLDER

Katharine S. Miller, Des Moines, Iowa

Application July 12, 1940, Serial No. 93,585

Term of patent 3½ years

To all whom it may concern:

Be it known that I, Katharine S. Miller, a citizen of the United States and a resident of Des Moines, in the county of Polk and State of Iowa, have invented a new, original, and ornamental Design for an Ash Holder, of which the following is a specification, reference being had to the accompanying drawing, forming part thereof, in which:

Fig. 1 is a perspective view of the ash holder showing my new design, and

Fig. 2 is a fragmentary, vertical sectional view of the holder with the lower portions omitted for convenience of illustration.

I claim:

The ornamental design for an ash holder, as shown.

KATHARINE S. MILLER.
